US00D573571S

(12) **United States Design Patent**
Morrison et al.

(10) **Patent No.:** US D573,571 S
(45) **Date of Patent:** ** Jul. 22, 2008

(54) **PORTABLE PHONE**

(75) Inventors: **Jasper Morrison**, London (GB);
Sang-Min Hyun, Seoul (KR);
Chang-Soo Lee, Incheon (KR);
Kyung-Jun Kwon, Hanam-si (KR)

(73) Assignee: **Samsung Electronics Co., Ltd.**,
Suwon-Si (KR)

(**) Term: **14 Years**

(21) Appl. No.: **29/287,204**

(22) Filed: **Jul. 10, 2007**

(30) **Foreign Application Priority Data**

Jan. 10, 2007 (KR) 30-2007-0001339

(51) **LOC (8) Cl.** **14-03**
